UNITED STATES PATENT OFFICE.

HELEN C. WINNIE, OF CHICAGO, ILLINOIS.

DESIGN FOR AN ICE-CREAM CONE.

Application filed February 11, 1924. Serial No. 8,606. Term of patent 3½ years.

To all whom it may concern:

Be it known that I, HELEN C. WINNIE, a citizen of the United States, residing in Chicago, in the county of Cook and State of Illinois, have invented a new, original, and ornamental Design for Ice-Cream Cone, of which the following is a specification.

In the accompanying drawing forming part of this specification—

Figure 1 is a view in elevation of an ice cream cone embodying my new design; and Figure 2 is a plan view looking down into the cone.

I claim:

The ornamental design for an ice cream cone as shown.

HELEN C. WINNIE.
